UNITED STATES PATENT OFFICE.

CARL HJALMAR LARSSON, OF SEATTLE, WASHINGTON.

SCAFFOLD-JACK.

1,394,178.

Specification of Letters Patent.

Patented Oct. 18, 1921.

Application filed January 2, 1920. Serial No. 348,819.

To all whom it may concern:

Be it known that I, CARL HJALMAR LARSSON, a subject of the King of Sweden, and resident of the city of Seattle, county of King, and State of Washington, have invented certain new and useful Improvements in Scaffold-Jacks, of which the following is a specification.

My invention relates to a scaffold jack 10 which is particularly adapted for use in connection with the scaffolding which is standard in ship-yards.

One object of my invention is to produce a jack which may be used to lift the planks 15 forming the scaffolding platform or the lateral spall which supports these planks, which jack may be supported either from the uprights themselves or from a lower spall or platform plank, as may be found 20 desirable.

Another object of my invention is to produce a scaffold jack which, in the form in which it would usually be used, would be sufficiently light in construction that it 25 might be manipulated by one man.

My invention comprises the novel parts and combinations thereof which are shown in the accompanying drawings, described in the specifications, and particularly defined 30 by the claims terminating the same.

In the accompanying drawings I have shown my invention in the form which is now preferred by me.

Figure 1 is an elevation of my invention 35 complete, parts being broken away, and shown in section.

Fig. 2 is an elevation of my invention looking at it from the side which is designed to be attached to the uprights.

Fig. 3 is a perspective of a standard ship-yard scaffolding illustrating my invention in use.

The standard shipyard scaffolding is composed of uprights formed of two timbers 5 45 spaced apart and placed in pairs of two, forward and rear, as shown in Fig. 3, and cross-braced with small timbers 50. In these pairs of uprights are supported the spalls 51. These are generally supported 50 by means of pins 52 which pass through holes 53 in the uprights and beneath the spalls or beneath their forward ends and above their rear ends, as the occasion may require. The pairs of uprights 5 are braced 55 one from the other by means of braces 54 between the rear uprights of each pair.

The forward ends of the spalls 51 are left projecting forward and upon them are supported the planks 55 which form a scaffold platform. These planks are generally quite 60 heavy, 2"x12" planks being the standard size, and generally three of these are supported side by side upon the projecting ends of the spalls.

In constructing a ship it is necessary to 65 change the position of the planks 55 and the spalls 51 frequently as the construction progresses, the planks 55 of one platform must be piled one upon the other and shoved back toward the uprights to give space for work- 70 men upon the platform below. The distance between the platforms is generally too small to permit the requisite freedom of movement. This method of procedure is illustrated at the right of Fig. 3. As construction progresses upward the platforms must be raised for the various gangs of 75 workmen and it is for doing this heavy lifting that my jack is designed. Ordinarily this work is performed by a number of men 80 working together and known as scaffold riggers. By the use of my invention this scaffold rigging may be done by one man instead of several.

There are often times in such work when 85 it is impossible to secure a firm support beneath a jack and for that reason I provide means whereby my jack may be supported from the uprights. As herein shown the nut 1, which has the screw 2 threaded therein, is provided with a pair of arms. The upper arm 10 is provided with means for engaging the rear of an upright 5, as the laterally projecting finger 11. The lower arm 19 is provided with means for engaging 90 the forward face of the upright 5. This I have shown as the projecting finger 18. I prefer also that the arm 19 should have a finger 17 which is adapted to engage with the side face of the upright. The fingers 100 11, 18, and 17, may be provided with short pins or calks which are adapted to project into the wooden upright to provide a more secure grip thereon. I prefer also that the arms 10 and 19 and the fingers secured to 105 these arms should be so formed that they may be interchangeably engaged with either side face of the upright. The reason for this is that it might be found impossible at times to secure the finger to the upright at 110 the desired position on account of interference by the braces 50. In this case the arms

may be moved to the opposite side of the uprights and engaged there.

Upon the upper end of the screw 2 I mount a scaffold supporting arm 21. This 5 may be pivotally mounted upon the end of the screw as by means of the ball 20 and the set collar 22. The spread of the arms 21 may be any amount desired. I prefer, however, that they be long enough to support the 10 three planks 55 as they lie side by side. If the scaffold supporting arm 21 extends to this length the entire platform may be lifted without disturbing its arrangement and without piling up the boards, and the spall 15 can then be raised or lowered while the jack supports the planks. The arm 21 may also be provided with calks as shown, for engaging the wooden planks. It may be turned horizontally at any angle desired and may 20 be engaged beneath the spall 51 to lift the platform in this manner.

At times it might be found desirable to support the jack from a platform or spall beneath it. I have, therefore, provided an 25 attachment which has a pair of legs 3 provided with feet 30 for supporting the device from a platform. The legs 3 as herein shown are supported in a cross arm 31 which is screwed upon the outside of the nut 1 at 30 32 or is secured thereto in any other suitable manner. Supplemental toes 33 are mounted upon the legs 3, these being adapted to engage upon the edges of the planks or spalls. I prefer that they be pivoted upon the legs 35 to swing laterally thereon so that they may be swung out of the way when not in use.

If desired ratchet means may be employed for turning the screw 2. As shown herein this consists of the arm 24 pivotally mounted 40 upon the lower end of the screw and carrying a spring pressed pawl 25 which engages with a ratchet pinion 26 secured upon the screw. For convenience in handling the device I may provide a handle 13 upon the 45 nut. I may also attach a chain and hook 14 to the nut, by means of which the jack may be hung in the scaffolding when not in use.

What I claim as my invention is:

1. Means for raising or lowering scaffolding 50 platforms comprising an attachment member and an elevator member engaged therewith and vertically movable therein, and supporting means for said attachment member comprising an upper arm having laterally-projecting fingers engageable with the rear face of a scaffold upright, and a lower arm having laterally-projecting fingers engageable with the forward face of 55 the upright.

2. Means for raising or lowering scaffolding- 60

ing platforms comprising an attachment member and an elevator member engaged therewith and vertically movable therein, and supporting means for said attachment member comprising an upper arm having laterally-projecting fingers engageable with the rear face of a scaffold upright, and a lower arm having laterally-projecting fingers engageable with the forward face of the upright, said lower arm having also a finger engageable with a side face of the upright, said supporting arms and fingers being interchangeably engageable with opposite side faces of the upright. 65

3. A scaffold jack comprising a nut and a 70 screw threaded therein, a scaffold support upon the upper end of said screw, means for supporting said nut by engagement with a scaffold upright, and supplemental supporting means adapted to be secured to said nut 75 and to support the jack from a horizontal portion of the scaffold.

4. A scaffold jack comprising a nut and a screw threaded therein, a scaffold support upon the upper end of said screw, means for 80 supporting said nut by engagement with a scaffold upright, and supplemental supporting means adapted to be secured to said nut 85 and comprising legs depending from the nut and having series of laterally projecting toes 90 adapted to engage horizontal portions of the scaffold.

5. A scaffold jack comprising a nut and a screw threaded therein, a scaffold support upon the upper end of said screw, means for 95 supporting said nut by engagement with a scaffold upright, and supplemental supporting means adapted to be secured to said nut and comprising legs depending from the nut and having series of laterally projecting toes 100 adapted to engage horizontal portions of the scaffold, said toes being pivotally mounted upon said legs.

6. In a scaffold jack, a nut provided with 105 means for supporting it from a scaffold upright, comprising an upper arm having two fingers laterally projecting in opposite directions, either finger being adapted to engage the rear face of a scaffold upright, and a lower arm having two fingers laterally projecting in opposite directions, either of said 110 last named fingers being adapted to engage the forward face of the upright, said lower arm having also a finger between the opposite laterally projecting fingers adapted to 115 engage a side face of the upright.

Signed at Seattle, King county, Washington, this 24th day of December, 1919.

CARL HJALMAR LARSSON.
